(57) **CLAIM**

The ornamental design for a nasal dilator, as shown and described.

DESCRIPTION

FIG. 1 is a top plan view of a first embodiment of a nasal dilator;

FIG. 2 is a perspective view of the nasal dilator of FIG. 1, where the nasal dilator is in a state of use;

FIG. 3 is a three-quarter perspective view of the nasal dilator of FIG. 1;

FIG. 4 is a top plan view of a second embodiment of a nasal dilator;

FIG. 5 is a perspective view of the nasal dilator of FIG. 4, where the nasal dilator is in a state of use; and,

(Continued)

FIG. 6 is a three-quarter perspective view of the nasal dilator of FIG. 4.

The broken lines showing human facial features are directed to environment and form no part of the claimed design.

1 Claim, 2 Drawing Sheets

Related U.S. Application Data

a continuation-in-part of application No. 13/437,929, filed on Apr. 3, 2012, now abandoned.
